(57) **CLAIM**

The ornamental design for a modular LED sign, as shown and described.

DESCRIPTION

FIG. 1 is a front perspective view of a modular LED sign showing our new design according to a first embodiment, in which a gaming machine is shown in broken lines to illustrate example environment;

FIG. 2 is an exploded front perspective view thereof, shown without the example environment;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view of a modular LED sign showing our new design according to a second embodiment, in which a gaming machine is shown in broken lines to illustrate example environment;

FIG. 9 is an exploded front perspective view thereof, shown without the example environment;

FIG. 10 is a front elevation view thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is a front perspective view of a modular LED sign showing our new design according to a third embodiment, in

(Continued)

which a gaming machine is shown in broken lines to illustrate example environment;
 FIG. 16 is an exploded front perspective view thereof, shown without the example environment;
 FIG. 17 is a front elevation view thereof;
 FIG. 18 is a right side elevation view thereof;
 FIG. 19 is a left side elevation view thereof;
 FIG. 20 is a top plan view thereof;
 FIG. 21 is a bottom plan view thereof;
 FIG. 22 is a front perspective view of a modular LED sign showing our new design according to a fourth embodiment, in which a gaming machine is shown in broken lines to illustrate example environment;
 FIG. 23 is an exploded front perspective view thereof, shown without the example environment;
 FIG. 24 is a front elevation view thereof;
 FIG. 25 is a right side elevation view thereof;
 FIG. 26 is a left side elevation view thereof;
 FIG. 27 is a top plan view thereof; and,
 FIG. 28 is a bottom plan view thereof.

The dashed broken lines illustrating a gaming machine in FIGS. 1, 8, 15, and 22 show environment that forms no part of the claimed design. The remaining dashed broken lines in the figures illustrate portions of the modular LED sign that form no part of the claimed design.
